UNITED STATES PATENT OFFICE.

EDWARD CROCHERON, OF DETROIT, MICHIGAN.

SYSTEM FOR EXTINGUISHING FIRES.

SPECIFICATION forming part of Letters Patent No. 638,911, dated December 12, 1899.

Application filed October 14, 1898. Serial No. 693,519. (No model.)

To all whom it may concern:

Be it known that I, EDWARD CROCHERON, a citizen of the United States, residing at Detroit, county of Wayne, State of Michigan, 5 have invented a certain new and useful Improvement in Systems for Extinguishing Fires; and I declare the following to be a full, clear, and exact description of the invention, such as will enable others skilled in the art to 10 to which it pertains to make and use the same, reference being had to the accompanying drawings, which form a part of this specification.

My invention relates to a new and improved 15 system for extinguishing fires and to devices for use therein. The system in use now consists in smothering or pounding out a fire by a great volume of water discharged directly upon the fire and usually from a great distance. The great distance necessary to throw 20 the water is due to the fact that the firemen are unable to approach the fire on account of smoke and heat.

The object of my invention is to provide 25 means whereby one or more firemen may approach a fire notwithstanding the volume of smoke produced thereby or the heat generated. The means employed by me for this purpose consist in employing the full volume 30 of water that can be carried by the ordinary hose or supply-pipe in the form of a wall or cloud of water in advance of the firemen, the water being divided or sprayed to such an extent as to cause it to practically fill the space 35 attacked by the firemen.

I am aware that the employment of a spray 40 to extinguish a fire is neither new nor of any particular value in the judgment of experienced firemen, and I do not claim the use of a spray merely as such.

In the drawings, Figure I represents a building 45 within which fire is burning attacked by firemen employing my system. Fig. II represents a form of nozzle that may be employed for the purpose.

In the drawings, Fig. I, on the right, a single fireman is represented as employing a discharge of water so expanded as to completely fill the room from the end. On the left two 50 firemen are represented as attacking the fire from the side where a greater area is to be covered.

The discharge-nozzle (shown in Fig. II) consists of an ordinary discharge, over which is fitted a cup-shaped distributing device consisting of an outer cup-shaped portion A, to which is attached an interior cup-shaped portion B, the interior portion rotating within the outer on the pivot a.

C is an annular flange, to which the outer 60 shell A is attached. The inner shell B is provided on the inside with a rack b, with which meshes the pinion b². This pinion is mounted on the shaft b³, which extends to the outside of the case and is rotated through the 65 beveled gear b⁴ and the crank b⁵.

By means of the construction just described the inner shell B can be rotated within the outer shell A. These shells are each provided with suitable openings for the discharge of 70 water, and the amount of water discharged and the size of the openings are regulated by the adjustment of the inner shell, whereby the openings are increased or decreased.

I do not limit myself to the form of nozzle 75 shown, as any form may be employed which will break up the heavy stream of water and cause it to expand into a moving cloud or spray. The requisites are simply to fill the space in front of the firemen with a large volume 80 of water divided into as fine particles or streams as possible. The result of the operation of such a stream is to move the smoke immediately in front of the firemen in the opposite direction and away from them and to 85 a large degree to precipitate the same with the water, it being a well-known fact that a fine spray of water will precipitate the particles of carbon constituting the smoke. At the same time that the forward-moving cloud 90 of water precipitates the smoke it likewise forms an impenetrable wall between the firemen and the heat, through which the heat will not radiate.

My invention is for use in all cases where 95 fire is found to be burning and not located, as the advance of the fireman with the heavy spray drives the smoke before him until the fire is located and the great extension of the spray covers the fire wherever located, and if 100 it is surrounding the room as on the wall, or ceiling, it is met by the cloud wherever it may be.

I do not claim for my device that it will ex-

tinguish a heavy fire in its last stages; but where it is confined to the room or rooms that may be approached by the firemen it can be reached much easier in this way than by the 5 use of a heavy stream thrown at random through the smoke and with much less danger of scattering the fire when found by the stream.

Having described my invention, what I 10 claim is—

1. A rain-nozzle consisting of an outer and an inner perforated distributing-shell, said shells arranged concentric to each other and in juxtaposition, a rack on one of said shells, 15 a pinion suitably mounted, meshing therewith and means for rotating said pinion, whereby one of said shells may be rotated

with reference with the other, substantially as described.

2. A rain-nozzle for extinguishing fires consisting of discharge-nozzle, an outer cup-shaped portion A an inner cup-shaped portion B concentric and in juxtaposition with the outer cup or shell A, said inner cup or shell provided with a rack, a pinion meshing with 20 said rack, and means for operating the same, substantially as described.

In testimony whereof I sign this specification in the presence of two witnesses.

EDWARD CROCHERON.
